F. O. v. TRAITTEUR

STOP CYLINDER PRINTING PRESS WITH FRONT DELIVERY

Filed April 11, 1924

Inventor:

Friedrich Oskar v. Traitteur

By *John Daniels*

Attorney.

UNITED STATES PATENT OFFICE.

FRIEDRICH OSKAR V. TRAITTEUR, OF FRANKENTHAL, GERMANY.

STOP-CYLINDER PRINTING PRESS WITH FRONT DELIVERY.

Application filed April 11, 1924. Serial No. 705,939.

To all whom it may concern:

Be it known that I, FRIEDRICH OSKAR V. TRAITTEUR, director of the Schnellpressenfabrik Frankenthal, Albert & Cie., citizen 5 of the German Republic, residing at Frankenthal, Rheinpfalz, Germany, have invented new and useful Improvements in Stop-Cylinder Printing Presses with Front Delivery, of which the following is a specification.

The present invention relates to improvements in printing presses with an intermittently stopped impression cylinder and a delivering table at the front end of the 15 press.

The delivery of the printed sheets of paper in printing presses with an intermittently arrested impression cylinder hitherto usually took place by means of a delivery 20 drum in connection with a reciprocating lever arrangement. All trials serving for the purpose of delivering the printed sheets at the front end of the press, that is to say the printed surface of the sheet lying above and 25 the top of the page in advance running in the direction from the apex of the printing cylinder in the direction of its revolution have never had a permanent success. Important disadvantages were the results of all 30 such trials, because the printed sheet of paper was drawn off from the stopped impression cylinder; and therefore the disadvantages which could not be overcome were essentially the following:

35 The sheet intimately adheres during the printing process to the cylinder especially in cases where thin sheets of paper are employed; therefore a strong holding friction is produced between both coacting parts 40 which friction must be overcome when the sheet is drawn off. This friction-resistance is considerably increased by the great size of the sheet surrounding the whole periphery of the printing cylinder. The amount 45 of the friction being at least $\frac{\pi}{2}$, even in the

case when the diameter of the cylinder being great enough to let the back edge of the sheet drop down. The unfavorable result of such arrangement therefor consists 50 in the fact, that the front edge of the paper where the latter is drawn off by the gripping or clamping device, is mutilated, especially if the sheet is fed several times 55 through the press. In the last mentioned case also differences in the register have been

observed due to the deformation of the paper. A further important disadvantage resides in the fact, that, when a sheet printed on both sides is drawn off or delivered, the first print is deposited on the surface of the cylinder. Finally the time for feeding in a fresh sheet of paper is shortened or reduced, so that the insertion of the new sheet of paper cannot more properly be executed by means of a resting table and registering devices provided on the printing cylinder, but is to be done by a governed table and governed gauge pin.

All other contrivances for diminishing the contact-friction by removing the sheet on the printing cylinder for instance by blowing air between the paper and the cylinder had no satisfying result, likewise no devices for decreasing the size of the sheet. The 70 said arrangements had merely as result a construction suitable for certain cases in practice. In printing presses with intermittently stopped cylinder the delivery device 75 consisting of a delivery drum in connection with oscillating levers remained as the single useful one in spite of all its disadvantages very well known (as for instance the adhering of the fresh print to the cylinder, to the delivery drum and to the feeding 80 strings and in spite of the limited velocity of the oscillating levers).

In stop cylinder presses the surface of the printing cylinder is covered by the sheet to be printed only by half. It may therefore be suggested to feed in the sheet near the lowermost point of the cylinder (at the contact point of the printing form with the printing cylinder), so that the sheet there is immediately printed upon whereupon after 90 the print has been finished, that is to say after nearly half a revolution counted from the apex of the cylinder; therefore the sheet may be fed to the delivery table by using the remaining half of the revolution of the 95 printing cylinder. This arrangement can not be executed in practice, because the delivery of the sheets would lie above the feeding table for the fresh sheets and the space necessary for the feeding table cannot be provided.

The invention now has for its principal object a front delivery for the single printed sheets, in which the above named disadvantage is entirely obviated. The feeding in device is here effected in the usual known manner by means of a table provided above and 100

— near the apex of the printing cylinder. Hence the sheet of paper is not immediately shifted to be printed upon but first to an auxiliary cylinder by means of a gripping device; from the said auxiliary cylinder the sheet is taken off by a second clamping or grasping device oppositely arranged in the printing cylinder at an angle of 180° (degrees), which second gripping device will 5 guide the sheet into the position for print and hence to the delivery front table of the printing press, to which the sheet of paper is fed by utilizing the last half of revolution of the printing cylinder. The inking duct 10 is arranged in this case below the feeding in table in opposition to the delivery drum. 15

In the annexed drawing the impression cylinder as well as the intermediate auxiliary cylinder has been represented in three 20 different positions during the working operation. Figure 1 is a cross-section of the impression and intermediate auxiliary cylinders showing the printing form in position in order to print the sheet, Fig. 2 is a 25 similar view showing the printing form as almost completing its back motion and the sheet has just been received by the take off arrangement, and Fig. 3 is another similar view showing the printing form in its complete back motion under the color feed and the sheet almost free from the take off arrangement. 30

Referring to the drawing, *a* represents the impression or printing cylinder having 35 two sets of grippers *d* and *f* arranged at practically opposite points on the cylinder. The sheet *e* is fed from a table and is transferred to the auxiliary cylinder *b* by means of grippers *m*. The printing form is represented by *c* and *i* and *k* are a plurality of feeding rollers for the take off tongues or reeds *h*. The non-impression gripper *d* transfers the sheet *e* to the cylinder *b* while the impression gripper *f* grips the sheet *g* 40 from the cylinder *b*. Therefore, the cylinder *a* has an impression surface and a non-impression surface. 45

The impression cylinder *a* in Figure 1 being at the end of its position of rest, 50 the printing form *c* has arrived in its dead-point at the left hand side; the grippers *d* are closed and have seized the sheet *e* for the purpose of feeding it to the auxiliary cylinder *b*, when the printing is started or driven again. The grippers *f* have taken 55 off the sheet *g*—in the manner represented— from the auxiliary cylinder for carrying it into the printing position.

Figure 2 shows the printing cylinder 60 after a revolution of approximately 240° (degrees). The print has been finished; the gripping device has guided the printed sheet over the apex of the printing cylinder to the delivery table represented in the drawing 65 by tongues or reeds *h* and the feeding rollers

i and *k*. The gripping device *d* has conducted the still unprinted sheet of paper to the auxiliary or transporting cylinder *b* which has received it by means of the gripping device *m*; the printing form has assumed its middle position. 70

Figure 3 shows the printing cylinder *a* after having finished a total revolution (i. e., about 360° in its position of rest). The printing form has reached its dead 75 point at the right hand side; the gripping levers *d* are opened for receiving a fresh sheet of paper *n*. The grippers have seized the sheet *e* from the auxiliary cylinder *b* and the printed sheet *g* has been delivered to the 80 front end table of the printing press. 85

I claim:

1. A stop cylinder printing press comprising an impression cylinder having an impression surface and a non-impression surface each provided with a gripper; and an auxiliary cylinder associated with the impression cylinder which is adapted to receive the sheet to be printed from the non-impression surface of the impression cylinder and transfer it to the impression surface of said impression cylinder in order to remove the printed sheet directly from the impression cylinder to prevent blurring of the ink. 90

2. A stop cylinder printing press comprising an impression cylinder having an impression surface and a non-impression surface each surface having a gripper; and an auxiliary cylinder associated with the impression cylinder which is adapted to receive the sheet to be printed from the non-impression surface of the impression cylinder and transfer it to the impression surface of said impression cylinder in order to remove the printed sheet directly from the impression cylinder to prevent blurring of the ink, said auxiliary cylinder being provided with a gripper. 100

3. A stop cylinder printing press comprising an impression cylinder having an impression surface and a non-impression surface each surface having a gripper; an auxiliary cylinder associated with the impression cylinder which is adapted to receive the sheet to be printed from the non-impression surface of the impression cylinder and transfer it to the impression surface of said impression cylinder in order to remove the printed sheet directly from the impression cylinder to prevent blurring of the ink, said auxiliary cylinder being provided with a gripper; and a feed table provided adjacent the impression cylinder adapted 110 to feed the sheets of paper to the non-impression surface of the impression cylinder. 115

4. A stop cylinder printing press comprising an impression cylinder having an impression surface and a non-impression surface each surface having a gripper; an 120

auxiliary cylinder associated with the impression cylinder which is adapted to receive the sheet to be printed from the non-impression surface of the impression cylinder and transfer it to the impression surface of said impression cylinder in order to remove the printed sheet directly from the impression cylinder to prevent blurring of the ink, said auxiliary cylinder being provided with a gripper; a feed table provided

adjacent the impression cylinder adapted to feed the sheets of paper to the non-impression surface of the impression cylinder; and an inking mechanism associated with the printing form and arranged below the feed table on the opposite side of the impression cylinder to that of the auxiliary cylinder. ¹⁵

In testimony whereof I have signed my name to this specification.

FR. v. TRAITTEUR.
